UNITED STATES PATENT OFFICE

2,151,423

INTERNAL COMBUSTION ENGINE

Henry Ford, Dearborn, Mich., assignor to Ford Motor Company, Dearborn, Mich., a corporation of Delaware

Application May 13, 1937, Serial No. 142,370

7 Claims. (Cl. 123—175)

The object of my invention is to provide a water circulating system for V-type motors which is believed to be unique in that a pair of water pumps are provided, one for each cylinder block, the pump housings therefor being cast integrally with the respective cylinder blocks. A feature of great importance in connection with this device is that the water pump shafts are lubricated directly by the oiling system of the engine so that the need of separate lubrication for the pumps is eliminated. More specifically, the water pumps are aligned with the cam shaft timing gear and passageways are provided whereby oil which is thrown radially from this timing gear is conducted to the bearings for the water pump shafts.

A further object of my invention is to provide a construction wherein a cover plate forms a housing for the cam shaft timing gears, the support for the two water pumps, and the means upon which the front end of the engine is mounted.

With these and other objects in view, my invention consists in the arrangement, construction and combination of the various parts of my improved device, as described in the specification, claimed in my claims and illustrated in the accompanying drawings, in which:

Figure 1 is a front view of a motor having my improved water circulating system incorporated therein.

Figure 2 is a sectional view, taken on the line 2—2 of Figure 1.

Figure 3 is a sectional view, taken on the line 3—3 of Figure 2.

Figure 4 is a sectional view, taken on the line 4—4 of Figure 2.

Figure 5 is a sectional view, taken on the line 5—5 of Figure 2, and

Figure 6 is a fragmentary view of one of the pump driving pulleys.

Referring to the accompanying drawings, I have used the reference numeral 10 to indicate the cylinder blocks of a V-type engine, which cylinder blocks are cast integrally with a crank case 11. An oil pan 12 is secured in the usual manner to the underside of the crank case. The engine is provided with a conventional crank shaft 13 and cam shaft 14, the two being geared together by timing gears 15 and 16, respectively. These gears 15 and 16 are secured to the crank shaft and cam shaft, respectively, at the forward end of the engine and project slightly beyond the forward ends of the cylinder blocks 10.

A combined timing gear housing and motor supporting bracket 17 is adapted to be secured to

the front end of the crank case 11 over the timing gears, this bracket being fastened thereto by means of a plurality of bolts 51. It will be noted from Figure 3 that the bracket 17 forms a housing around the cam shaft timing gear 16 and that this bracket has a pair of arms 18 cast integrally therewith which arms extend horizontally beyond the cylinder block so as to form a pair of spaced supports for the front end of the motor.

I have provided two water pumps, one for each cylinder block, these pumps being mounted upon the bracket 17 and having their impellers extending into suitable pump housings which are cored into the cylinder block casting 10. The bracket 17 is provided with a pair of annular chambers 19 cored therein, each of these chambers being longitudinally aligned with and on opposite sides of the timing gear 16. The chambers 19 are in communication with the timing gear housing so that when the engine is operating, oil will be thrown radially from the timing gear and will enter each of these chambers. It will be noted that the bracket 17, adjacent to each chamber 19, is formed with both inner and outer walls, the inner wall bearing against the front end of the cylinder block. Two pairs of aligned tapered openings extend respectively through the inner and outer walls of the bracket 17. Each pair of these openings is aligned with one of the chambers 19 so as to each receive a water pump unit. Each water pump proper comprises a cylindrical body 20 having an annular bore therethrough in which a bearing sleeve 21 is secured. A flange 22 extends radially from the inner end of the member 20, the periphery of this flange being tapered to correspond to the tapered bore in the inner wall of the bracket 17. An outer flange 23 extends radially from the body 20 at a point spaced from the outer end thereof, the periphery of this outer flange also being tapered to correspond to the tapered opening in the outer wall of the bracket 17. Thus, when each pump unit, as so far described, is inserted into the tapered openings, the flange 23 forms a seal with the outer face of the bracket 17 while the flange 22 forms a seal with the inner face of this bracket. These two flanges thereby prevent oil which is deposited in the chambers 19 from leaking through to the outside of the motor and also prevents the leakage of water into the chambers 19. A felt sleeve 47 is placed around each member 20, which sleeves become saturated with oil which is thrown from the timing gear. An oil hole 53 extends through each member 20 and bearing sleeve 21

so that oil will flow from the felt sleeve 47 to the shaft 30 and thereby lubricate the pump.

In order to secure each pump in position plates 24 are provided, each having a pair of arms 25 which are adapted to straddle the center portion of the member 20 and bear against the periphery of the outer flange 23. The inner ends of each plate 24 are adapted to bear against a flange 26 which is formed around the periphery of a distributor housing 27. The distributor housing is designed to be secured to the outer wall of the bracket 17 directly in line with the cam shaft 14, the distributor having a tongue formed thereon which coacts with a groove 28 formed in the cam shaft 14. A stud 29 is threaded into the bracket 17 between each of the pump openings and the distributor, upon which studs each of the plates 24 is secured so that upon the screwing down of a suitable nut each plate 24 will be secured in position with the arms 25 bearing against the pump flange 23, while the inner ends of each plate bear against the flange 26 of the distributor. In this manner the distributor is secured to the bracket 17 and each of the pump housings is secured in the pump receiving openings.

It will be noted from Figure 2 that a pump shaft 30 is rotatably mounted in each of the bearings 21, each shaft having a radially extending flange 31 formed integrally therewith at the outer end of the bearing sleeve 21. A cap 32 is threaded upon the outer end of the member 20, this cap coacting with the flange 31 to prevent axial movement of the shaft in bearing sleeve 21 and a V-belt pulley 33 is pressed on the outer end of each shaft 30. The drive for the pump is obtained in the conventional manner, there being a driving pulley 34 which is secured to the crank shaft and a combined fan and generator pulley 35 which is aligned with the pulleys 33 and 34, in position at the top of the motor. A V-type belt 36 extends around the four pulleys so as to drive all pulleys simultaneously.

Referring to Figure 2, I have shown an impeller 37 which is adapted to bear against the inner face of the flange 22. A tongue and slot driving connection 52 is provided between the impeller 37 and the shaft 30 and further, the impeller is piloted in axial alignment with the shaft by allowing the shaft to project a short distance into the impeller. However, the impeller is not fixed to the inner end of the shaft as a small universal movement is permitted between the shaft and the impeller so that the impeller may form a watertight connection between its back and the inner face of the flange 22. A Bakelite button 38 is secured in the inner end of the impeller at the axis thereof and three vanes 39 extend radially from the hub of the impeller. A flat spring 40 has its respective ends secured to the periphery of the flange 22, the spring extending around the face of the impeller and having a seat at its central portion with which the button 38 coacts so that the impeller is resiliently urged against the inner face of the flange 22. Each pump is designed to be assembled as a unit, each unit comprising the pump body, pulley, shaft, impeller and spring. After the unit is assembled it is then inserted into the tapered openings in the bracket 17 and the pump is ready to operate.

It will be noted from Figure 4 that the outer walls of each cylinder block are formed from a metal plate 41 which is welded to the block around its periphery. Each cylinder block is provided with a volute shaped chamber 42 cast therein in axial alignment with the axes of the

water pumps when the bracket 17 is secured in position. Openings are provided in the forward end of the cylinder block so that the impellers 37 may project into the chambers 42, the latter forming housings for the water pumps. A pair of chambers 43 are cast in the cylinder blocks rearwardly of the chambers 42 and an axial opening 44 connects each chamber 42 with the adjacent chamber 43. The openings 44 are smaller than the path described by the impeller vanes 39 so that when the impellers are rotated, water will be drawn from the chambers 43 through the openings 44 and discharged into the chambers 42. An intake pipe 45 is fixed to each plate 41 so as to discharge into the chamber 43 adjacent to the bottom of the cylinder block. The chambers 42 are in communication with passageways 46 which extend longitudinally the full length of the cylinder block, the passageways 46 comprising outer water jacket for each cylinder block. A cylinder head 48 is secured over the upper end of each cylinder block in the conventional manner and aligned openings 49 are provided in the cylinder blocks and heads whereby water may circulate from around the cylinders to the cylinder heads. An outlet opening 50 is provided in each cylinder head 48 at the upper side thereof so that water may be discharged from the motor.

When the engine is in operation, the impeller draws water through each pipe 45, chambers 43 and 42 and discharges same into the passageway 46. Part of the water then flows the length of the motor, the remaining part flowing upwardly around each of the cylinders in the block. The water is then discharged through the openings 49 into the water chambers around the cylinder heads and then flows outwardly through the outlets 50. Suitable hose, connect the outlets 50 with the radiator of the vehicle and likewise connect the bottom of the radiator with the inlet pipes 45.

Among the many advantages arising from the use of my improved construction, it should be kept in mind that the pumps are lubricated by the oil which is circulated in the motor so that failure of the pumps because of lack of lubrication is practically impossible. This feature simplifies the servicing of the engine and further prevents water pump failures due to the negligence of owners in not lubricating same.

Still further, by casting both the inlet and outlet housings of the motor with the cylinder block casting a substantial saving of the cost of the installation is effected.

Some changes may be made in the arrangement, construction and combination of the various parts of my improved device without departing from the spirit of my invention and it is my intention to cover by my claims such changes as may reasonably be included within the scope thereof.

I claim as my invention.

1. An internal combustion engine having a water jacket formed therearound, a bracket secured to said water jacket to thereby form a chamber outside of said jacket, said chamber being in direct communication with the crank case of said engine, aligned openings in said bracket and water jacket, and a water pump extending through said openings, and forming a seal with said bracket and water jacket respectively, the intermediate portion of said pump being exposed within said chamber, for the purpose described.

2. A device, as claimed in claim 1, wherein said

openings are tapered and wherein said pump is provided with correspondingly tapered seats which coat therewith to form said seals.

3. A fluid pump adapted to circulate cooling fluid through an internal-combustion engine comprising, a pump body having a pump shaft rotatably mounted therein, an impeller secured to said shaft at one end of said body, driving means secured to said shaft adjacent to the other end of said body, the periphery of said body having a pair of axially spaced concentric annular sealing surfaces thereon, and means for securing said pump in an internal-combustion engine with said sealing surfaces coacting with complementary sealing surfaces in said engine.

4. A fluid pump adapted to circulate cooling fluid through an internal-combustion engine comprising, a pump body having a pump shaft rotatably mounted therein, an impeller secured to said shaft at one end of said body, driving means secured to said shaft adjacent to the other end of said body, the periphery of said body having a pair of axially spaced concentric sealing surfaces thereon, said surfaces both being conical in shape, and means for securing said pump in an internal-combustion engine with said sealing surfaces coacting with complementary sealing surfaces in said engine.

5. A fluid pump adapted to circulate cooling fluid through an internal-combustion engine comprising, a cylindrical body member having a pump shaft rotatably mounted therein, an impeller secured to said shaft at one end of said body, driving means secured to said shaft adjacent to the other end of said body, said body member having a pair of flanges extending radially from the respective ends thereof, the peripheries of said flanges each being tapered to

coincide with the surface of a cone the axis of which is aligned with said pump shaft, and means for securing said pump in an internal-combustion engine with said flanges coacting with complementary sealing surfaces in said engine.

6. A fluid pump adapted to circulate cooling fluid through an internal-combustion engine comprising, a cylindrical pump body having a pump shaft rotatably mounted therein, said body having a pair of flanges extending radially from axially spaced points therealong, an impeller secured to said shaft adjacent to one end of said flanges, said impeller member coacting with a flat face on the adjacent flange to form a fluid seal between the cooling fluid and said shaft, a driving pulley secured to the opposite end of said shaft, the peripheries of said flanges being machined to coincide with the surface of a cone the axis of which is in alignment with the axis of said shaft and the apex of which is disposed at the impeller end of said shaft, and means for securing said pump in an engine with said flange peripheries coacting with a pair of complementary conical surfaces in said engine so that a seal is maintained between each of said flanges and said engine.

7. An internal-combustion engine comprising, a cylinder block having a water jacket cast therearound, one side of which is open, said water jacket having water pump inlet and outlet chambers cast therein, a portion of each of said inlet and outlet chambers being exposed adjacent to said open portion of the water jacket, and a plate secured to said block over said water jacket and housings, said plate forming a closure for said water jacket and pump housings.

HENRY FORD.
